(57) **CLAIM**

The ornamental design for a credit card grabber, as shown and described.

DESCRIPTION

FIG. 1 is a perspective view of one part of the credit card grabber showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of another part of the credit card grabber showing my new design;

FIG. 10 is a perspective view thereof from another angle;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a combined perspective view thereof.

The broken lines depict portions of the credit card grabber that form no part of the claimed design.
